STATIC ELIMINATOR FOR RADIO
TELEGRAPHY

Thomas W. Holden, Fort Wayne, Ind.

Application August 18, 1941, Serial No. 407,343

1 Claim. (Cl. 250—8)

This invention relates to improvements in static eliminators for radio telegraphy, and an object of the invention is to provide in connection with a radio telegraphic receiver an adjunct capable of diverting from the received radio current, such as passes through an antenna circuit, detrimental influences that generally are caused by inherent radio electrical disturbances or forces or different frequencies.

Another object of the invention is to afford, in an adjunct for a radio telegraphic receiver, a circuit including a coil influenced by the output current from a telegraphic receiver, over which is carried a normal signal and including the static disturbances, a second circuit including another coil influenced approximately only by the static effect imparted through the telegraphic receiver, and a make and break mechanism influenced oppositely by the magnetic fields of said coils and connected in another circuit with a telephonic receiver.

Other objects and advantages of the invention appear in the following description.

An illustrative embodiment of the invention is shown in the accompanying drawing, in which:

Fig. 1 is a diagram showing the relative arrangement of the various parts and electrical circuits of the adjunct and a radio telegraphic receiver;

Fig. 2 is a side elevational view of an oscillating shaft and parts connected therewith forming an element of the appliance;

Fig. 3 is a fragmentary cross-sectional view, the section being on the line X—X in Fig. 1; and

Fig. 4 is a detail showing a top plan view of a make and break device associated with the audio circuit.

The illustrative embodiment of the invention consists of a radio telegraphic receiver 1, of any suitable type for the transmission of code signals received through an antenna circuit, having connected therewith a primary audio circuit including conductors 2 and 3 provided with corresponding extensions thereof 2' and 3', in which are connected in series a variable resistance member 5, telephonic receiver 4 and another variable resistance member 6, in the order as named. A secondary audio circuit is provided consisting of continuations 2'' and 3'' of said extensions, in which secondary circuits are connected, in series, an electrical make and break controlling device hereinafter described, and in parallel, a condenser 7 located between said device and said resistance member 6. The controlling device consists of a standard 8 provided with a base 9,

and an oscillating shaft 10 pivotally supported in the standard, there being an adjusting screw 11 in the standard engaging one end of the shaft by which the shaft is delicately supported to have free axial oscillating movement. Upon the standard is mounted a bracket 12 of insulating material provided with a spring contact tongue 13 that is electrically connected with the continuation 2'' of the audio-circuit wire 2', and upon the shaft 10 is mounted a finger 14 that overlaps and, upon turning of the shaft in one direction, has contact with the tongue. Threaded stops 15 and 16 oppositely disposed in the bracket are arranged to limit movement of the finger therebetween.

Upon the bracket are mounted major and minor electro-coils, A and B, disposed obliquely respecting the shaft 10 in parallel planes and encompass said shaft which extends through their axes at the medial points thereof.

Upon the shaft 10 are mounted a pair of iron vanes 17 and 18 that slant oppositely with respect to each other and are located within the magnetic fields of the respective coils, so that upon energizing of the coils, torque is exerted on the shaft in opposing directions.

Upon a stud 19 projecting from the base 9 is mounted a regulating lever 20, one end of which is provided with a handle 21 and its opposite end 22 is slotted and extends astride and secures the outer end 23 of a balance spring 24 that consists of a coiled metal band. The inner end of the spring is secured to the shaft 10. By adjustment of the lever 20 upon the stud, angularly with respect to the axis of the shaft, the shaft is normally held, through the medium of the spring, so that the contact finger 14 is disposed in neutral position out of contact with the tongue 13 whereby the secondary audio circuit through the continuation 2'', tongue 13, contact finger 14, shaft 10, base 9, and continuation 3'' is then open.

The conductors 2 and 3 have continuations 25 and 26 respectively between which is connected an adjustable resistance 27 provided with an adjustable contactor 28, and also there is connected between the continuations 25 and 26 a bridge tone circuit in which are included the resistances 27 and 29, condenser 30 and a choke coil 31. The contactor 28 is connected with one terminal of the minor coil B by a conductor 32, the opposite terminal of said coil being connected with the continuation 25 at a point between the resistance 29 and the condenser 30 by a conductor 33. Preferably, the continuation 25 has

connected therein a manually operated switch 34 located between the connections therewith of the adjustable resistance 27 and the audio circuit wire 2'.

The opposite terminals of the major coil A are connected respectively with the continuation 25 and the conductor 3 respectively by means of branches 35 and 36, and there is connected in said branch 36 another variable resistance 37.

In this system there are included a primary audio circuit (2-2'-5-4-6-3' and 3); a secondary audio circuit

(2-2'-5-4-2''-13-14-3''-3' and 3);

a coil A energizing circuit

(2-35-36-37 and 3)

a coil B energizing circuit

(2-25-29-33-32-28-27-26 and 3)

and a tuned bridge circuit (27-29-30 and 31) connectedly related with the coil B energizing circuit, designed for sensitiveness to a definite signal cycle. By this arrangement, when the switch 34 is closed the normal output flow of current from the receiving set 1 is distributed to the coils A and B through their respective energizing circuits and to the phone 4 through the primary audio circuit. By adjustment of the variable resistance member 37, the volume of flow through the respective coils is brought to equality and their magnetic effect thus balanced. By adjustment of the lever 20 the shaft 10 through the medium of the balance spring 24 is turned to neutral position so the switch (13-14) is open. Upon occurrence of each signal impulse, in the output from the set 1 at a selected frequency, the flow of current through the coil A is thereby increased, while coincidentally the signal impulse is intercepted in the bridge circuit because of resonance occasioned and is therefore eliminated from the energizing circuit of the coil B. Under this circumstance, the coils A and B become unbalanced, the coil A having superior force in turning the shaft 10 in switch closing direction, thus resulting in closing of the secondary audio circuit. Concurrently, therewith, any radio frequency generated at the switch contacts 13-14 is bypassed by the condenser 7 and thus eliminated from the input circuit of the receiver. Thus, upon each signal impulse the secondary audio circuit is closed and the phone 4 energized enabling the operator to detect the signal.

By adjustment of the variable resistance 5 the volume of current passing through the phone is modified as desired.

Operation

In using the invention, the output of the receiving set 1 is admitted to the primary audio circuit while the switch 34 is open, and the volume is reduced by adjustment of the resistance member 6 so sound is faintly audible through the phone 4. The switch 34 is then closed and the contactor 28 is adjusted to a point where the resistance of the two arms of the bridge circuit are in balance. The coils A and B are then balanced by adjustment of the resistance member 37, and the switch 13-14 is positioned in neutral or open position by adjustment of the lever 20.

The minor coil B, upon closing of the switch 34, is brought into connection with the primary audio circuit, the flow of current therethrough being modified by the resistance 29 and the adjustable resistance 27, and is additionally affected by the condenser 30 and the choke coil 31 of the bridge between the conductor 33 and the continuation 26. By these arrangements the flow of current through the coils A and B differ: The current passing through the major coil A, bears the characteristics of the audio output flow from the telegraphic receiver and includes the signal and static influences, while the flow of current through the minor coil B is distinguishable in that it is characterized only by the effects of the static influence emanating through the output of the telegraphic receiver. The currents thus differing in character, passing through the coils A and B, create opposite or varying influences upon the respective vanes 17 and 18, whereupon, the shaft is angularly turned upon its axis, in one direction or the opposite, according to the greater or lesser magnetic influence of the coils on the vanes.

Operation of the make and break circuit is influenced because of torque exerted oppositely by current passing through the major and minor coils and their co-related vanes on the shaft 10. Ordinarily, due to the unequal opposing influences of the currents passing through the major and minor coils upon their respective vanes, the contact finger 14 on the shaft is moved into or out of contact with the spring tongue 12, whereupon the make and break circuit is closed or opened accordingly in unison with the signal impulses passing through coil A, to which the telephonic receiver is responsive.

Variations from the particular construction above disclosed may be resorted to by the exercise of skill in the art, without departure from the spirit or scope of the invention, and the following claim is intended to be inclusive of such variations.

What I claim is:

43. In a static eliminator for a radio telegraphic receiver, an electrically operated make and break device consisting of a standard having thereon a stationary contact member, an oscillator pivoted in said standard provided with a finger engageable with said member, said member and finger being electrically connected in the audio circuit of said receiver, major and minor electro coils positioned on said standard in slanting parallel planes, iron vanes secured on said oscillator in oppositely slanting planes and disposed respectively in the magnetic fields of said coils so the oscillator is influenced oppositely when the coils are energized, a balance spring on the oscillator provided with an adjuster therefor, and electrical means associated with said audio circuit including individual circuits for said coils through which the major coil is energized by current derived from said audio circuit characterized by signal and static influences, and the minor coil is energized by current derived from the same source characterized exclusively by the static influence whereby the static influences in said coils counterbalance each other and the oscillator is actuated by the signal influence of the current passing through the major coil.

THOMAS W. HOLDEN.
